CLAIM

The ornamental design for a hose connector, as shown and described.

DESCRIPTION

FIG. 1 is a perspective view of a first embodiment of a hose connector;

FIG. 2 is an end view of the hose connector of FIG. 1 (as taken from the left end of the connector in FIG. 1);

FIG. 3 is an end view of the hose connector of FIG. 1 (as taken from the right end of the connector in FIG. 1);

FIG. 4 is a front view of the hose connector of FIG. 1;

FIG. 5 is a rear view of the hose connector of FIG. 1;

FIG. 6 is a top view of the hose connector of FIG. 1;

FIG. 7 is a bottom view of the hose connector of FIG. 1;

FIG. 8 is a perspective view of a second embodiment of a hose connector;

FIG. 9 is an end view of the hose connector of FIG. 8 (as taken from the left end of the connector in FIG. 8);

FIG. 10 is an end view of the hose connector of FIG. 8 (as taken from the right end of the connector in FIG. 8);

FIG. 11 is a front view of the hose connector of FIG. 8;

FIG. 12 is a rear view of the hose connector of FIG. 8;

FIG. 13 is a top view of the hose connector of FIG. 8; and,

FIG. 14 is a bottom view of the hose connector of FIG. 8. The broken lines depict portions of the hose connector that form no part of the claimed design.

1 Claim, 6 Drawing Sheets
